UNITED STATES PATENT OFFICE.

CARLETON RUHE, OF OLEAN, NEW YORK.

HYDROPLANE.

1,233,708.

Specification of Letters Patent. Patented July 17, 1917.

Application filed August 22, 1916. Serial No. 116,270.

To all whom it may concern:

Be it known that I, CARLETON RUHE, a citizen of the United States, residing at Olean, in the county of Cattaraugus and State of New York, have invented certain new and useful Improvements in Hydroplanes, of which the following is a specification.

My invention relates to improvements in hydroplanes.

An important object of the invention is to improve the construction of hydroplanes in general with a view of rendering them more reliable in operation, and convenient to control in such operation.

A further object of the invention is to provide a hydroplane which may be safely driven at a high speed.

A further object of the invention is to provide improved and efficient means for forcing air through the openings in the sustaining or stabilizing planes.

Other objects and advantages of the invention will be apparent during the course of the following description.

In the accompanying drawings forming a part of this specification and in which like numerals are employed to designate like parts throughout the same,

Figure 1 is a plan view of a hydroplane embodying my invention,

Fig. 2 is a side elevation of the same,

Fig. 3 is a central vertical longitudinal sectional view through the same,

Fig. 4 is a bottom plan view of one of the sustaining or stabilizing planes,

Fig. 5 is a transverse sectional view taken on line 5—5 of Fig. 2,

Fig. 6 is a plan view of gearing,

Fig. 7 is a vertical longitudinal sectional view through a suction fan or mechanism, and,

Fig. 8 is a transverse sectional view taken on line 8—8 of Fig. 7 with parts broken away.

In the drawings, wherein for the purpose of illustration is shown a preferred embodiment of my invention, the numeral 10 designates the hull or body portion of the hydroplane. This hull has a forward bottom portion 11, which is approximately V-shaped in cross-section, as shown in Fig. 5, and tapers downwardly. The forward end of this bottom portion inclines upwardly, as clearly shown in Fig. 2, and this forward end is tapered, as shown. The rear portion of the bottom of the hull is off-set upwardly, pro-

viding an elevated rear bottom portion 12, which is curved in cross-section and has its concave surface arranged outermost. As more clearly shown in Figs. 2 and 5, the bottom portion 11 has edge portions 13 which are transversely flat, and vertical vanes or blades 14 are rigidly secured to the edge portions 13 and depend therefrom, as shown. The upper portion of the hull is preferably closed by a top portion 14, and this top portion has an opening 15.

Arranged upon opposite sides of the hull 10 and rigidly attached thereto are sustaining or stabilizing planes 16, which are identical. Each plane 16 is provided centrally thereof with a longitudinally extending air chamber 17, the lower wall of which is provided with discharge apertures or openings 18. As more clearly shown in Fig. 4, the apertures or openings 18 are uniformly distributed upon the lower wall of the air chamber 17 and gradually increase in size toward the center of the lower wall.

Suitably arranged within the hull is an internal combustion engine 19, preferably of the V-type, and preferably comprising two sets of cylinders, each set comprising four cylinders. The engine has an exhaust pipe 19', which discharges into the passage beneath the bottom portion 12, as shown. The engine 19 comprises a crank or driving shaft 20, which extends parallel with the longitudinal axis of the hull and projects outwardly beyond the rear thereof.

Arranged upon the opposite sides of the shaft 20, within the hull 10, and near the rear end of the engine 19, are air suction fans or pumps 21, which are identical. As more clearly shown in Figs. 7 and 8, each suction fan or pump comprises a shell 22, rigidly attached to the hull 10 and this shell is provided with an air intake 23, as shown. The outlet side of shell 22 has connection with an air supply conduit 24, which is connected with the plane 16, and discharges into the air chamber 17. Disposed for rotation within the casing 18 is a tube 25, having apertures 26. This tube has the end thereof of extending into the conduit 24 open while its opposite end is closed and rigidly connected with a driving shaft 27. Rigidly mounted upon the rotatable tube 25 are suction fans 28, comprising spaced disks 29, carrying therebetween curved vanes 30. These propeller fans rotate in the direction of the arrow, as shown in Fig. 8, and the air passes inwardly between the vanes 30.

and discharges through the openings 26 into the tube 25. The air passes from the tube 25 into the conduit 24 and then into the air chamber 17. The air passes from the air chamber 17 through the openings 18.

Rotation is imparted to the shafts 27 by means of sprocket wheels 31, rigidly secured thereto and which are engaged by sprocket chains 32. The sprocket chains 32 extend 10 inwardly to engage sprocket wheels 33, which are rigidly mounted upon the shaft 20.

The propelling means for the hydroplane comprises an air propeller 34, rigidly secured to the rear end of the shaft 20, and a water propeller 35, which is driven by a shaft 36. The shaft 36 is journaled through a bearing 37 and extends forwardly in proximity to the forward end of the crank shaft 20 and is connected therewith by means of 20 suitable gearing 38.

Attached to the rear end of the hull 10 are horizontally swinging direction rudders 39, turned by cranks 40. The cranks 40 are connected by a drag-link 41 which 25 may be moved by any suitable means (not shown).

In the operation of the machine, the air which is exhausted from the fans 21 pass into the air chambers 17 and to the atmosphere through the apertures 18. The amount of air supplied to the air chambers from the air fans or pumps is in excess of that discharging through the perforations 18, whereby a substantial degree of pressure 30 is built up and maintained within the air chambers 18. The exhaust air passing through the perforations or openings 18 comes in contact with the air of the atmosphere exteriorly of the chambers 17, and 35 when the hydroplane is traveling at a high rate of speed, the air exhausting through the apertures 18 contacts with the outside air, with the result that there is a tendency to elevate the hull out of the water, which 40 in turn will aid in eliminating friction between the hull and the water. The propelling of the boat is effected by means of the air propeller 34 and the water propeller 35, as is obvious.

50 It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described the invention what I claim is:—

60 1. In a hydroplane of the character de-

scribed, a hull having a forward bottom portion which is approximately V-shaped in cross-section and tapers downwardly, and an upwardly off set rear bottom portion which is curved in cross-section with its concave surface arranged outer-most; longitudinal substantially vertical vanes secured to the forward bottom portion of the hull near its outer edges and depending therefrom; an internal combustion engine arranged within the hull; propelling means for the hull which are driven by the engine; and steering means connected with the hull.

2. In a hydroplane of the character described, a hull having a forward bottom portion which is approximately V-shaped in cross-section and tapers downwardly, and an upwardly off set rear portion which is curved in cross section with its concave surface arranged outermost; longitudinal 75 vanes secured to the forward bottom portion of the hull near its edges and depending therefrom; an internal combustion engine arranged within the hull and having an exhaust pipe which discharges into the 80 passage beneath the rear bottom portion of the hull; and propelling means for the hull which are driven by the engine.

3. In a hydroplane of the character described, a hull having a forward bottom portion which is approximately V-shaped in cross-section and tapers downwardly, and an upwardly off set rear bottom portion which is curved in cross-section with its concave surface arranged outer-most; longitudinal 90 vanes secured to the forward bottom portion of the hull near its outer edges and depending therefrom; an explosive engine arranged within the central portion of the hull and having 95 a crank-shaft extending to the rear end of the hull; air pumps disposed upon opposite sides of the engine and attached to the hull and geared to the crank-shaft to be driven thereby; conduits connected with the outlet sides of the pumps; sustaining or stabilizing planes attached to the opposite sides of the hull and having air chambers provided with downwardly discharging apertures, such air chambers having communication with the conduits; an air propeller connected with the rear end of the crank-shaft; and a second propeller driven by the engine.

In testimony whereof I affix my signature in presence of two witnesses.

CARLETON RUHE.
